UNITED STATES PATENT OFFICE.

FREDERICK NEWNHAM CHRISTIAN, OF TAURANGA, NEW ZEALAND.

MEANS FOR DRAWING LIQUID FROM RECEPTACLES.

1,028,542.

Specification of Letters Patent.

Patented June 4, 1912.

Application filed September 21, 1911. Serial No. 650,506.

To all whom it may concern:

Be it known that I, FREDERICK NEWNHAM CHRISTIAN, subject of the King of Great Britain, residing at Tauranga, in the Dominion of New Zealand, have invented a new and useful Improved Means for Drawing Liquid from Receptacles; and I do hereby declare the following to be a full, clear, and exact description of the same.

10 This invention has been designed for use in drawing off motor fuel-oil from the cans in which they are contained and for emptying the contents into the tanks of the motors.

15 The invention consists in the combination with a funnel adapted to fit into the opening of the tank and to rest on its edge, of a triangular support for holding the can secured upon the top of the funnel and provided with a piercer device for piercing the can so that its contents may flow into the funnel and through it, into the tank.

20 In fully describing the invention, reference will be made to the accompanying drawings, in which:—

25 Figure 1 is a side elevation of the appliance. Fig. 2 is a sectional side elevation thereof. Fig. 3 is a plan of the can holder. Fig. 4 is a plan of the funnel. Fig. 5 is a 30 sectional elevation on an enlarged scale of the piercer attachment to the can holder.

35 A is the funnel which is shaped as shown to fit over the mouth of the tank opening and with a downward extension A' adapted to pass into such opening. It is also provided with the strainer B situated above the extension so as to strain the liquid passing through the funnel.

40 C is the triangular support for the can. This support is arranged on the top of the funnel so that its apex extends down into it, and its side angular edges are arranged to fit into rests D formed in the top edge of the funnel, while its back angular edge 45 is supported by the stay E extending up from the edge of the funnel. The support is firmly fixed to the funnel by riveting or otherwise, but preferably by means that will permit of them being taken apart when desired so that the funnel strainer may be cleaned.

45 The support C is adapted to receive a corner of the can and to extend over its bottom and sides in such a manner as to hold the can placed within it, as shown by the dotted lines in Fig. 1. The angle at which

it is fixed in the funnel is such that the can of suitable dimensions will be held without any other aid.

Upon the bottom of the support is fixed 60 the piercer device. This consists of a hollow pointed cone G arranged to project from the bottom and fixed over an opening H therein. The cone is formed with apertures J in its side, so that liquid may flow through 65 such apertures into the cone and down through it into the funnel. It is provided with an air aperture K arranged above the apertures J and below which a small pipe M leads downward and out through the 70 bottom of the support C, its bottom end then being bent sidewise as shown.

In use the can to be emptied is placed within the support in the manner indicated and pressed down so that the cone piercer G 75 will pass in through its end. The liquid will then flow out through the apertures J and down into the funnel, the necessary air to cause the flow being admitted through the pipe M and aperture K. In this manner the tin will be emptied of the whole of its contents without any attention. A small hole N is made in the bottom corner of the support to permit of any liquid leaking out around the outside of the piercer, falling 85 into the funnel.

What I do claim as my invention, and desire to secure by Letters Patent is:—

1. In means for the purpose described, a funnel, a substantially right trihedral support fixed upon the top of the funnel and adapted to receive the corner of a can and to support the tin, and a hollow piercer projecting from the lower part of the support, adapted to enter the can and to lead its contents into the funnel, substantially as specified.

2. In means for the purpose described, a funnel adapted to fit upon a tank opening, a strainer across the mouth of the funnel, a substantially right trihedral support fixed on the top of the funnel, and a hollow piercer projecting upward from an aperture in the bottom of the support formed with apertures in its side and provided with an 100 air admission pipe opening through its side above such apertures, substantially as herein specified.

3. In a device of the class described, a funnel having upstanding sides adapted to 110 rest firmly upon a tank, and having an extension adapted to fit into the tank opening;

a strainer in said funnel; an inverted substantially right trihedral support of sheet material and having an opening near the apex thereof, and secured on said upstanding sides with its apex over said extension and adapted to receive one corner of a rectangular can and support the same; a cone piercer secured with its base surrounding said opening of the support, and extending parallel to one edge of the support and having elongated apertures near the base and

a vent aperture near the apex; and a pipe extending throughout the opening of the support to said vent aperture.

In testimony whereof, I have signed this 15 specification in the presence of two subscribing witnesses.

FREDERICK NEWNHAM CHRISTIAN.
